UNITED STATES PATENT OFFICE.

RICHARD A. WEISSE, OF BROOKLYN, NEW YORK.

MACHINE FOR FOLDING AND CUTTING TEXTILE AND PAPER STRIPS.

1,098,538.

Specification of Letters Patent.

Patented June 2, 1914.

Application filed March 19, 1913. Serial No. 755,391.

To all whom it may concern:

Be it known that I, RICHARD A. WEISSE, a citizen of Germany, residing at Brooklyn, county of Kings, and State of New York, have invented a new and Improved Machine for Folding and Cutting Textile and Paper Strips, of which the following is a specification.

This invention relates to a machine of novel construction for folding textile and paper strips and for cutting them up into pocket book gussets, index tabs or similar articles.

Briefly stated the machine comprises a pair of folders of which the first folder is adapted to turn over the two longitudinal edges of the strip to form a pair of flanges, while the second folder is adapted to double the flanged strip upon itself. The strip is drawn through the folders by means of a pair of feed rolls placed in advance thereof, while a cutter placed, in turn, in front of the feed rolls, cuts up the folded strip into the lengths desired. The feed rolls and cutter are operated from the power shaft by means of a transmission, which actuates the same alternately, so that the strip will be at rest while being cut.

In the accompanying drawing: Figure 1 is a plan of a folding and cutting machine embodying my invention; Fig. 2 a side elevation thereof; Fig. 3 a face view of the strip-edge folder; Fig. 4 a longitudinal section on line 4—4, Fig. 3; Fig. 5 a face view of the strip-doubling folder; Fig. 6 a longitudinal section on line 6—6, Fig. 5; Fig. 7 a cross section on line 7—7, Fig. 3; Fig. 8 a cross section on line 8—8, Fig. 5; Fig. 9 a perspective view of a gusset formed by the machine, and Fig. 10 a perspective view of a similarly formed index tab.

From the base plate 10 of the machine frame extends an upright spindle 11, upon which is free to turn a spider 12 that supports the roll 13 of a paper or textile strip or tape 14. This strip is carried around a pair of guide pins 15, 16 extending upwardly from arms 17, that are bolted to plate 10 at 18. Upon each of the pins 15, 16 is mounted a collar 19, which supports a friction sleeve 20 that loosely encompasses the pin, a curved guard 21 carried by a collar 19, serving to hold the strip 14 in contact with the sleeve.

From pin 16, strip 14 is carried through the first folder A, and thence through the

second folder B, by means of a pair of feed rolls 22, 23 placed in advance of folder B, and which will be referred to more fully later on.

The first folder A is composed of a plate 24 placed edgewise and provided at its outer side with an eye or hub 25, which loosely encompasses a spindle 26 that extends upwardly from an arm 27 bolted to plate 10 at 28. The top and bottom edges of plate 24 are turned over more and more from the receiving or rear end toward the delivery or front end of the folder, so that there are formed a pair of gradually widening vertically disposed longitudinal flanges 29, while the body of the plate is correspondingly tapered or reduced. At the receiving end of the folder, there is furthermore secured to plate 24 a cross bar 30, to form a flat eye 75 through which the strip 14 is threaded. A pair of inwardly extending guide lugs 31 are further provided at those points where the flanges 29 take a pronounced turn, while an additional pair of inwardly extending guide lugs 32 is provided at the forward end of plate 24 directly in front of flanges 29. These lugs 32 are made integral with a flat resilient bar 33 attached to plate 24 at 34, so that there is provided a certain play between plate and lugs. From the body of cross bar 30, there is stamped out a hook 35 that engages the slotted heel 36 of a flat tongue 37. This tongue faces the operative or flanged inner side of plate 24 toward 85 which it is held by lugs 31, 32, and thus presses strip 14 tightly against such plate. The free end of tongue 37 is straddled by the flanges 29 and is longitudinally slotted as at 38 to increase its flexibility. As the strip 14 is drawn through the folder, its longitudinal edges will be gradually upset by the taper of plate 24 and flanges 29 against the exposed side of tongue 37, so as to form the desired edge flanges 39 upon the 90 fabric strip, in which condition the latter is delivered to the second folder B.

The second folder is composed of a plate 40 having at its inner side an eye or hub 41 which is free to turn loosely on a spindle 42 that extends upwardly from an arm 43 bolted to plate 10 at 44. Plate 40 is gradually bent or doubled upon itself from its rear toward its front end to form a pair of jaws 45, which converge from the rear toward 110 the front, at which latter point they assume a substantially horizontal position.

By the construction described, plate 40 is made substantially of trough-shape, the ingress end of the trough being provided with an upright guide bar 46 forming an eye for strip 14, while the egress end of the trough is provided with a horizontal guide eye 47 encompassing the ends of jaws 45. In order to hold strip 14 tightly against the outer concave operative side of the trough, bar 46 carries a tongue 48 which co-operates with a pair of doubled spring fingers 49, between which the tip of the tongue projects. It will be seen that as the strip received from folder A is drawn through folder B, it will be doubled upon itself along its longitudinal axis, as at 50, Fig. 9 to assume the gusset shape desired. If the first folder A be removed from its spindle and the second folder B only be used, then the strip will not be provided with end flanges, but only with the central fold as indicated at 50 Fig. 10. Thus it will be seen that the machine is adapted to fold the strips either thrice or once only, the former adjustment being used for making say pocket book gussets, while the latter adjustment is used for making say reinforcing finger pieces or index tabs for blank books, etc. It may here be added that by pivotally mounting the folders upon the machine bed, they will be automatically swung into a true position by means of the pull exercised upon the strip 14 by the feed rollers, so that their proper alinement is at all times assured. So also by the peculiar construction of the folders, those doubled portions of the strip which occur from time to time, wherever the end of one strip unit is pasted over the corresponding end of the succeeding strip unit, will pass freely underneath the root of the tongues and the yielding lugs 32, so that they will not interfere in any wise with the free operation of the machine.

As has been stated, the feed rolls 22, 23 are located directly in advance of the second folder B. The stud 51 of lower roll 23 is mounted in an arm 52 which is pivoted at 53 to a standard 54 and has an extension 55 engaged by a set screw 56. Between arm 52 and base plate 10, is interposed a coiled spring 57, the tension of which is thus regulable by the set screw, and which serves to press roll 23 against the driven upper roll 22. The means for imparting intermittent movement to roll 22, comprise a power shaft 58 journaled in a standard 59 and adapted to be coupled to a pinion 60 by means of a clutch 61, said clutch being operated by a hand lever 62 adapted to be locked by latch 63. Pinion 60 meshes into a large gear wheel 64, to the outer face of which the rear end of a driving rod 65 is connected by wrist pin 66 and slide 67, so that in this way the stroke of the rod is regulable. The forward end of rod 65 engages an oscillative

arm 68 loosely turning on a shaft 69 and provided with a pair of pawls 70. These pawls engage a ratchet disk 71 fast on one face of a toothed wheel 72 that is intergeared with a pinion 73 turning on the stud 74 of roll 22, said pinion being rigid with said roll. This pinion is connected to a toothed wheel 75 of said roll which is intergeared with a corresponding wheel 76 of lower roll 23. It will be seen that by the construction described, the forward stroke of rod 65 will by pawls 70 and ratchet disk 71 impart the desired feed movement to rolls 22, 23, while during the back stroke of the rod, the pawls will ride idly over said disk, so that in this way the movement of the rolls is rendered intermittent in the manner desired.

In advance of the feed rolls, there is provided a guide or eye 77 for strip 14, while in advance of this guide, there is provided a cutter for dividing the strip into the lengths desired. This cutter may be either straight or it may be differently shaped to accord with the shape to be given to the severed strip-lengths, a curved cutter being for example used for cutting the lengths shown in Fig. 10. The upper movable cutting blade 78 is fitted to a head 79 rocking on a shaft 80, which is journaled in a block 81, said block constituting likewise a support for the guide 77 as well as for the fixed cutting blade 82 that co-operates with the movable blade 78. Head 79 is normally swung up by means of a coiled spring 83 fitted upon shaft 80 and engaging with one end a disk 84 fast on the shaft and with its other end a hub 85 integral with head 79. From this hub, there extends a tappet 86 engaging the forward arm 87 of a two arm lever which lever is fulcrumed at 88. The rear arm 89 of this lever is adapted to be engaged by a pin 90 projecting from the inner face of wheel 64, some distance back of wrist pin 66. Thus it will be seen that when rod 65 performs its back stroke and rolls 22, 23 are consequently at rest, the rear lever arm 89 will by pin 90 be depressed to correspondingly tilt cutter-head 79 downward by the engagement of front lever arm 87 with tappet 86. In this way, the knife 78 is swung down against the action of spring 83 to sever the desired section off strip 14, after which the knife is immediately swung up by spring 83, which comes into action as soon as the pin 90 has cleared the lever.

It will be seen that the machine constructed as described will fold and cut the strips into gussets, tabs or similar articles, in a quick, accurate and workmanlike manner.

I claim:

1. A machine of the class described, comprising a frame, a folder mounted thereon, a pair of feed rolls in front of the folder, a pivoted cutter-head having a tappet, a knife

carried by the cutter-head, a driven disk, a driving rod operated thereby, an oscillable arm connected to the driving rod, pawls on the arm, a ratchet wheel engaged by the 5 pawls, and fast on one of the feed rolls, and a lever also operated by the driven disk and engaging the cutter-head tappet.

2. In a machine of the class described, a folder comprising a tapering plate having 10 a pair of flanges of gradually increasing width, a cross bar at the back of said plate, a hook on the cross bar, and a tongue having a slit that is engaged by said hook.

3. In a machine of the class described, a 15 folder comprising a tapering plate having a pair of flanges of gradually increasing width, a resilient bar secured to the plate and a pair of lugs on said bar that extend in front of said flanges.

20 4. In a machine of the class described, a

folder comprising a tapering plate having a pair of flanges of gradually increasing width, a cross bar at the back of said plate, a slotted tongue removably secured to said cross bar, a resilient bar attached to the 25 plate, and a pair of lugs on said resilient bar that extend in front of said flanges.

5. In a machine of the class described, a folder comprising a plate doubled upon itself to form a pair of jaws that gradually 30 converge toward the front of the plate, a cross bar at the back of said plate, a tongue extending from said cross bar along the plate, and a pair of doubled resilient fingers flanking said tongue.
